UNITED STATES PATENT OFFICE

1,984,109

FASTENING-SUPPLYING APPARATUS

Frederick J. Balcom, Binghamton, N. Y., assignor
to United Shoe Machinery Corporation, Pater-
son, N. J., a corporation of New Jersey

Application August 8, 1932, Serial No. 627,876
13 Claims. (Cl. 1—39)

My invention relates to the supplying of fastenings, it being particularly concerned with apparatus for delivering nails for use in heel-attaching machines and the like.

5 When a nail-feeder or other fastening-distributor, such as that of Letters Patent of the United States No. 1,657,630, Lund, Jan. 31, 1928, is provided with means for causing the discharge of successive loads of nails as a result of direct actuation of its nail-roll or discharge device by the transferring or loading mechanism to which it delivers, a discharge-controlling arrangement of this character being disclosed in Letters Patent of the United States 10 No. 1,768,831, Dostie, July 1, 1930, the power means for actuating the discharge-roll and which stops the nail-advancing movement of the distributor-raceway, as is illustrated in the first-mentioned patent, is absent from the apparatus. 15 Unless means is taken to prevent it, the shake of the raceway will continue during discharge, with a possible tendency to displace the nails from the roll.

An object of my invention is to so control 20 the operation of a fastening-distributor as to insure the cessation of the raceway-movement before the discharge of the fastenings begins, the arrangement specially lending itself to co-operation with the roll-actuating means of the Dostie patent. This object I attain by transmitting the movement of the loading or transferring mechanism through a movable member to the discharge device for the fastenings and by controlling the movement of the raceway 25 from the member as the sole means of applying power while the discharge device remains at rest. In this way, the separation and discharge of successive loads of fastenings may be produced without the possibility of disturbance resulting from raceway-movement. For this purpose, there are shown herein governing connections from the raceway-controlling means to the movable member between the transferring mechanism and the discharge device. These 30 connections preferably first disengage a clutch through which the driving shaft of the distributor is rotated, stopping the power-operation of the apparatus, and thereafter the discharge-roll is actuated to make its delivery. In the 35 preferred form of my invention, the loader-actuated means consists of a plurality of members, as a rod or its equivalent having two independently movable sections, one of the sections or members having connections to it solely for 40 governing the raceway-oscillating mechanism,

while to the other are connections for oscillating the discharge-roll. Between these sections, arrangement is made for the introduction of initial lost motion to give an opportunity to produce one controlling effect before the other. 5 The inclusion of means to vary the effective length of one of the members gives an opportunity to vary the extent of movement of the discharge-roll in one direction while maintaining constant the time-relation thereto of the 10 raceway-control.

In the accompanying drawing is illustrated one of several forms which my invention may assume. Here,

Fig. 1 shows in perspective the delivery-portion of a nail-distributor resembling that of Lund;

Fig. 2 is a broken side elevation of the delivery-end of such distributor, together with a loader-arm which receives nails from the distributor for transfer to the nailing mechanism of a heel-attaching machine, and actuating connections from the loader-arm to the distributor, the elements being in their nail-delivering relation; and

Fig. 3 is a detail in side elevation of the connection between the sections of the distributor-controlling rod while in their normal position.

At 10 may be seen the nail-conducting raceway of a distributor D. The nails are delivered to raceway-grooves 12 by a rotatable drum or other power-driven means (not illustrated) and are caused to travel down the grooves by the oscillation of the raceway. For this purpose, said raceway is pivoted, as at 14, upon levers 16 fulcrumed upon the frame 18 of the distributor and rocked through connecting-rods, one of which appears at 20, it being driven by an eccentric 22 upon a main shaft 24 journaled transversely of the frame. Power may be applied to the shaft through a belt-pulley 26 and clutch 28. This clutch is held normally in engagement, so the shaft is rotated, by a spring 30. Disengagement may be effected by a hand-lever 32 fulcrumed upon a bracket 34 projecting from the frame, and this separation of the clutch members may be maintained, as when it is desired to fully stop the operation of the apparatus, by a latch 36 upon the lever, which enters a notch in a projection 38 from the bracket. All the power-driven elements of the distributor are preferably actuated from the shaft 24. Gearing 40 may be utilized to turn the nail-drum, and gearing 42 may oscillate the 45

usual clearing fingers 44 co-operating with the raceway.

To discharge the nails from the raceway in successive loads, the grooves 12 deliver through 5 openings 46 in a roll 48 journaled transversely of the raceway for oscillation between a receiving position, in which the openings are aligned with the grooves, and a delivering position, as shown in Fig. 2, the openings now being inclined 10 downwardly so the nails pass by gravity through tubes 50 to enter openings in a loader-block 52, by which they are to be transferred to the nailing mechanism of the machine supplied. The block 52 is carried by a loader-arm 54 mounted 15 to turn about a vertical spindle 56 fixed in the frame of the machine supplied and movable by the operator between positions for the reception of the nails from the distributor-tubes 50 and the delivery of said nails to the machine. 20 Upon the upper side of the loader-arm is secured a member on which is a cam-surface 58 arranged to strike, as the loader-block approaches the receiving end of its travel, the contact-portion 60 of an actuating rod *r*. This 25 rod appears as formed in lower and upper sections. The lower section 66 is guided in a bracket 68 secured to the spindle 56, and includes an angular end-portion 70 so attached at 72 to the body of the rod by a threaded connection that the effective length of the section 30 may be varied. In this end-portion 70 is shown a vertical socket to receive the reduced cylindrical extremity 74 of the upper rod-section 76. The section 76 is guided for vertical movement 35 in a bracket 78 attached to the distributor-frame 18, and is joined by a link 80 to a gear-segment 82 pivoted upon the raceway. The segment meshes with a pinion 84 fast upon the discharge-roll, and a spring 86, joining the segment to the frame, rotates the roll to normally 40 align its passages 46 with the raceway-grooves 12. The angular position of the roll for the reception of the nails may be adjustably determined by a screw 88 threaded through an arm 90 projecting from the end of said roll opposite 45 the segment 82 and contacting with the raceway. Formed upon the portion 70 of the lower rod-section 66 is a rack 91, with which meshes a pinion 92 fast upon the end of a shaft 93 journaled in the bracket 78 and in an opposite bracket 94. Secured to the shaft 93 outside 50 the bracket 94 is a cam 96, which engages, as the roll oscillates, a plunger 98 guided for reciprocation upon the bracket 94. A helical spring 100 surrounds the plunger, urging it toward 55 the cam. Threaded into the opposite end of the plunger is a contact-screw 102, against the head of which bears a contact-block 104 carried by the inner end of the hand-lever 32.

Upon starting the apparatus in operation, the 60 latch of the hand-lever 32 is released from the member 38, allowing the spring 30 to cause the engagement of the clutch 28. The pulley 26 being constantly driven by its belt, the shaft 24 now turns, producing rotation of the nail-drum 65 through the gearing 40 and delivery from said drum to the raceway-grooves 12; the oscillation of the raceway through the eccentrics 22, with the consequent forward travel of the nails along 70 the grooves; and movement of the clearing fingers 44 through the gearing 42. The roll 48 remains at rest, with its openings 46 in registration with the raceway-grooves, so it receives 75 a load of nails therefrom. When the operator is ready to perform a nailing operation, the

loader-arm 54 is swung manually into nail-receiving position, with the block 52 beneath the lower ends of the distributor-tubes 50. During this movement, the cam-surface 58 upon the loader-arm strikes the contact-piece 60 of the rod *r*, elevating the section 66 of said rod. Initially, the rod-sections are related as appears in Fig. 3 of the drawing, there being a space between opposed contact-surfaces 106, 106 of the sections. Consequently, the lower section travels upwardly for a time, while the upper section and the discharge-roll geared to it remain at rest. During this movement, the rack 91 and pinion 92 cause the rotation of the shaft 93. The cam 96, rotating with the shaft, has such a 15 contour that it forces the plunger 98 against the contact-end 104 of the lever 32 to separate the members of the clutch 28, but without engaging the latching members 36 and 38. Rotation of the shaft 24 is thus stopped, and the movement 20 of the nail-drum, raceway and clearer is discontinued. When all these elements of the nail-feeding means are at rest, the rod-section 66 has been elevated to a point at which contact 25 is established between the surfaces 106, 106. Continued movement of the lower section now raises the upper rod-section 76, swinging the gear-segment 82 to rotate the discharge-roll 48. This causes the entire discharging operation 30 of the nails from the openings 46 to occur while all the power-driven elements of the nail-feeding means are motionless, and there is nothing to jar the nails upon the roll so they will waste and clog. When the operator causes the delivering movement of the loader-arm after 35 the nails have been received in the block, the roll 48 is restored by the spring 86 to its normal relation, and the rod-section 76 correspondingly lowered. The rod-section 66 descends under the influence of gravity, turning the cam 96 so the 40 spring 100 may retract the plunger 98, and the lever 32 is released to permit the spring 30 to again engage the clutch 28 to start the nail-feeding operations. At any time it is desired to fully stop the operation of the apparatus, the 45 lever 32 is shifted by the operator to the maximum extent to disengage the clutch, it being latched at 38. Variation in the position of the portion 70 of the rod *r* upon its carrier-section 66 determines the extent to which the roll 48 50 is turned for discharge, and alteration in the position of the screw 102 changes the time of disengagement of the clutch. The latter adjustment having been made, the adjustment at 72 affects the roll and cam-actuated plunger simultaneously, so the proper relation between the roll-oscillation and clutch-release may be maintained.

Specific reference has been made to the nail-distributor of the Lund patent, which is designed for feeding at the same time nails of different lengths. It is to be understood, however, that my invention is equally applicable to a single-length nail-distributor.

Having thus described my invention, what I 65 claim as new and desire to secure by Letters Patent of the United States is:

1. The combination with fastening-feeding mechanism having a movable raceway, a discharge device and means for controlling the 70 movement of the raceway, of means movable to transfer fastenings from the feeding mechanism, a member extending to the discharge device and through which the movement of the transferring mechanism is transmitted to said 75

- discharge device, and connections to the member between the transferring mechanism and the discharge device for governing the controlling means.
- 5 2. The combination with fastening-feeding mechanism provided with an oscillatory discharge-roll, a main driving shaft for operating said fastening-feeding mechanism, and a clutch through which power is applied to the shaft, 10 of transferring means movable to receive fastenings from the feeding mechanism, a member movable by the transferring means, and connections to the member transmitting its movement as the sole means of applying power for first 15 engaging the clutch and thereafter oscillating the discharge-roll.
3. The combination with a nail-distributor having an oscillatory raceway, an oscillatory discharge-roll to which nails are delivered from the 20 raceway and mechanism for oscillating the raceway, of loading mechanism movable into position to receive nails falling from the discharge-roll, a member movable by the loading mechanism, connections to the member by which its 25 movement is communicated to the discharge-roll, and connections to the member excluding the discharge-roll and made effective by its movement before it moves said roll for governing the raceway-oscillating mechanism.
- 30 4. The combination with a nail-distributor having a movable raceway, a movable discharge-roll and actuating means for the raceway, of a loader-arm movable by the operator into nail-receiving position at the distributor, a rod movable by the loader-arm, and means for applying the force created by the operator through the rod first to the raceway-actuating means and thereafter to the discharge roll.
5. The combination with a nail-distributor 40 having an oscillatory raceway, an oscillatory discharge-roll to which nails are delivered from the raceway and mechanism for oscillating the raceway, of loading mechanism movable into position to receive nails falling from the discharge-roll, a plurality of members movable successively by the loading mechanism, connections to one of the members solely for governing the raceway-oscillating mechanism, and connections to another member for oscillating the discharge-roll.
- 50 6. The combination with a nail-distributor having an oscillatory raceway, an oscillatory discharge-roll to which nails are delivered from the raceway and mechanism for oscillating the raceway, of loading mechanism movable into position 55 to receive nails falling from the discharge-roll, a plurality of members movable by the loading mechanism, means arranged to vary the effective length of one of the members, connections to one of the members solely for governing the raceway-oscillating mechanism, and connections to another member for oscillating the discharge-roll.
- 60 7. The combination with a nail-distributor having an oscillatory raceway, an oscillatory discharge-roll to which nails are delivered from the raceway and mechanism for oscillating the raceway, of loading mechanism movable into position 65 to receive nails falling from the discharge-roll, a member movable by the loading mechanism, connections to said member for governing the raceway-oscillating mechanism, and a member 70 movable by contact with the raceway-governing member for oscillating the discharge-roll.
8. The combination with a nail-distributor having an oscillatory raceway, an oscillatory discharge-roll to which nails are delivered from the raceway and mechanism for oscillating the raceway, of loading mechanism movable into position to receive nails falling from the discharge-roll, a member movable by the loading mechanism, means arranged to vary the effective length 10 of said member, connections to said member for governing the raceway-oscillating mechanism, and a member movable by the raceway-governing member for oscillating the discharge-roll.
9. The combination with a nail-distributor 15 having an oscillatory raceway, an oscillatory discharge-roll to which nails are delivered from the raceway and mechanism for oscillating the raceway and including a clutch, of loading mechanism movable into position to receive nails falling from the discharge-roll, a rod movable by the loading mechanism and having independently movable sections, means rotatable by one section and acting upon the clutch, and connections to the other section for rotating the discharge-roll.
10. The combination with a nail-distributor 20 having an oscillatory raceway, an oscillatory discharge-roll to which nails are delivered from the raceway and mechanism for oscillating the raceway and including a clutch, of loading mechanism 25 movable into position to receive nails falling from the discharge-roll, a rod movable by the loading mechanism and having sections one of which acts upon the other with initial lost motion, means movable by the initiating section for actuating the clutch, and connections to the other section effective after the taking up of the lost motion for rotating the discharge-roll.
11. The combination with a nail-distributor 30 having an oscillatory raceway, a discharge device to which nails are delivered from the raceway and mechanism for oscillating the raceway and including a clutch, of loading mechanism 35 movable into position to receive nails falling from the discharge device, a rod movable by the loading mechanism, a shaft rotatable by the rod, and means actuated by the shaft for disengaging the clutch.
12. The combination with a nail-distributor 40 having an oscillatory raceway, a discharge device to which nails are delivered from the raceway and mechanism for oscillating the raceway and including a clutch, of loading mechanism 45 movable into position to receive nails falling from the discharge device, a rod movable by the loading mechanism, a shaft geared to the rod, a cam rotatable by the shaft, and connections actuated by the cam for disengaging the clutch.
13. The combination with a nail-distributor 50 having an oscillatory raceway, an oscillatory discharge-roll to which nails are delivered from the raceway and mechanism for oscillating the raceway and including a clutch, of loading mechanism 55 movable into position to receive nails falling from the discharge device, a rod movable by the loading mechanism, a shaft journaled adjacent to the rod, gearing connecting the rod and shaft, a cam rotatable by the rod, and a plunger movable by the cam and acting upon the 60 clutch.
